DESIGN FOR A FOOD PLATTER

Ernest J. B. La Lumiere, Cranston, R. I.

Application October 26, 1933, Serial No. 49,558

Term of patent 7 years

To all whom it may concern:

Be it known that I, ERNEST J. B. LA LUMIERE, a citizen of the United States, and residing at Cranston, Rhode Island, and whose post-office address is 112 Grace Street, have invented a new, original, and ornamental Design for a Food Platter, of which the following is a specification, reference being had to the accompanying drawing, forming a part thereof.

Fig. 1 is a top plan view of the article showing my new design.

Fig. 2 is a side elevation, and

Fig. 3 is a central vertical section through Fig. 1.

I claim:

The ornamental design for a food platter, substantially as shown.

ERNEST J. B. LA LUMIERE.
